(57) **CLAIM**

The ornamental design for a hunting blind connector, as shown and described.

DESCRIPTION

FIG. 1 is a top isometric view of a first embodiment of a hunting blind connector, showing my new design;

FIG. 2 is a bottom isometric view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is top plan view thereof.

FIG. 8 is bottom plan view thereof.

FIG. 9 is top isometric view of a second embodiment of a hunting blind connector, showing my new design;

FIG. 10 is bottom isometric view thereof;

FIG. 11 is front elevational view thereof;

FIG. 12 is right side elevational view thereof;

FIG. 13 is rear elevational view thereof;

FIG. 14 is left side elevational view thereof;

FIG. 15 is top plan view thereof; and,

FIG. 16 is bottom plan view thereof.

1 Claim, 6 Drawing Sheets
